UNITED STATES PATENT OFFICE

168,142

FOUNTAIN DISPLAY DEVICE

Everett Benjamin Castle, Cheverly, Md.

Application July 22, 1952, Serial No. 20,713

Term of patent 14 years

(Cl. D80—1)

To all whom it may concern:

Be it known, that I, Everett B. Castle, a citizen of the United States residing at Cheverly, county of Prince Georges and State of Maryland, have invented a new, original, and ornamental Design for a Fountain Display Device, of which the following is a specification, reference being had to the accompanying drawings forming part thereof, and in which drawings:

Figure 1 is a front perspective view of a Fountain Display Device showing my new design; and

Figure 2 is a rear perspective view thereof.

I claim:

The ornamental design for a fountain display device, as shown.

EVERETT B. CASTLE.
